SCREED FOR CEMENT SURFACES

Ralph G. Barnes, Portland, Oreg., assignor of one-half to Jesse J. Gard, Portland, Oreg., and one-half to Master Vibrator Company, Dayton, Ohio, a corporation of Ohio:

Application May 7, 1949, Serial No. 92,017

8 Claims. (Cl. 94—48)

This invention relates to concrete vibrators of the kind characterized by a vibratory screed or beam.

In the use of devices of this type, the beam is supported at or adjacent to its ends and is dragged over the surface of the work, for example, a roadway in which fresh concrete has been poured. The tendency of the beam to sag or bow when so supported and used has precluded the use of elongated beams, which would be more efficient and desirable in some applications. Moreover, in equipment of this type no means have been heretofore provided whereby a predetermined bow or arch may be adjustably imparted to the beam, adapting the screed for work upon concave and convex surfaces.

The instant invention contemplates an improvement upon concrete screeds of the class described to the end that both limitations above mentioned may be obviated. A trussing of the screed or beam is proposed through a rigid "bridge" resisting sagging of the screed, a feature of the truss residing in adjustment means whereby the truss may be lengthened and shortened relatively to the screed. According to the construction and arrangement of parts, therefore, the screed or beam may be flexed to an arched or bowed contour or may be held rigidly in a flat horizontal plane, all in accordance with the requirements of the work. The invention further contemplates the improvement and simplification of the means of adjustably securing the supporting members to the vibratory screed.

The object of the invention is to simplify the construction as well as the means and mode of operation of vibratory screed beams whereby such devices may not only be economically manufactured, but will be more efficient and satisfactory in use, adaptable to a wide variety of work, having relatively few parts and be unlikely to get out of repair.

A further object of the invention is to provide in a vibratory screed means for adjustably flexing the screed for the finishing of contoured surfaces.

A further object of the invention is to provide a screed beam of extraordinary length, which may be accurately controlled as to contour.

A further object of the invention is to provide in an elongated vibratory screed means for controlling the flexing thereof intermediate its widely spaced points of supports.

A further object of the invention is to simplify the means and mode of adjustably securing supporting members to the ends of a vibratory screed.

A further object of the invention is to provide a vibratory screed possessing the advantageous structural features, the inherent meritorious characteristics and the mode of operation herein-mentioned.

With the above primary and other incidental objects in view as will more fully appear in the specification, the invention intended to be protected by Letters Patent consists of the features of construction, the parts and combinations thereof, and the mode of operation, as hereinafter described, or illustrated in the accompanying drawings, or their equivalent.

Referring to the accompanying drawing, wherein is found the preferred but obviously not necessarily the only form of embodiment of the invention;

Fig. 1 is a perspective view of a vibratory screed in accordance with the instant invention, showing a manner of use thereof;

Fig. 2 is a view of the vibratory screed in front elevation, partly diagrammatic, indicating how the beam may assume a flexed contour;

Fig. 3 is a detail view in front elevation of one end of the screed, showing the mounting means for the beam;

2

Fig. 4 is an end view of the screed partly in section, being taken along the line 4—4 of Fig. 3;

Fig. 5 is a fragmentary view similar to Fig. 4 but looking at the opposite end, being taken along the line 5—5 of Fig. 3;

Fig. 6 is a detail view partly broken away of the adjustment means embodied in the truss; and

Fig. 7 is a detail view partly in section showing the linkage interconnecting the truss and the screed.

10 Like parts are indicated by similar characters of reference throughout the several views.

The present disclosure represents a further development and improvement in the screed shown and claimed in my Patent No. 2,542,979, issued February 27, 1951.

15 Referring to the drawings, a vibratory screed in accordance with the instant invention is shown being used in the construction of a roadway or the like, spaced ledges or side forms 10 providing support for the device at its opposite ends. The screed is guided in its advance over the fresh concrete by men walking on the ledges 10 and produces a smooth compacted surface 11 as compared with the rough unfinished surface 12 which may be seen in advance of the device.

The screed comprises an elongated beam 13 of inverted T-shape, the beam being formed with a broad flat base portion 14 (see Fig. 4) and an upstanding web portion 15. Secured, as by welding, to the upper edge of the web portion 15 of the beam is a tube 16 which, in conjunction with the beam, is productive of a general and uniform amplitude of vibration. Centrally of the beam 13 U-bolts 17 project outwardly and upwardly from the opposite sides of web portion 15 and support a table 18 upon which is mounted a source of power 19 (a gasoline engine or electric motor). The power source 19 is connected to a rotary unbalanced weight (not shown) arranged beneath the table, rotation of which serves to vibrate the beam 13 to compact the surface on which it rests.

20 The structure so far described is substantially the same as that shown and described in my above-identified pending application for United States Letters Patent.

For better vibratory action the beam 13 is resiliently mounted upon its supports. As shown in Figs. 3 and 4, there is provided adjacent each end of the beam a two-part clamp 21 arranged to be compressed into gripping engagement with the tube 16 by adjustment of nut assemblies 22. Overlying the upper end of each clamp 21 is one end of a leaf spring 23 secured between the clamp and a plate 24 by a nut and bolt assembly 25. Each spring 23 extends axially of the beam 13 toward respective ends thereof and is fastened at its opposite end to a bracket 26 of inverted U-shape. The opposing legs of each bracket 26 extend downward in embracing relation to the tube 16 and beam 13 and are bent outward at their ends to define flanges 27 lying in a plane parallel to the base 14 of the beam 13. Secured to the flanges 27 are feet 28. Through the use of shims 29 placed between the feet 28 and flanges 27 accurate positioning of the feet may be accomplished in order that they may lie in a plane slightly lower than the base 14 of the beam 13 which thus is held in an elevated position yieldingly supported by the leaf springs 23. The feet 28 are adapted to ride upon a track or slideway, for example, the ledges 10 shown in Fig. 1.

65 According to the width of the surface being worked, the distance between such tracks or slideways will vary. Adjustment of the mounting means relative to the beam to allow for such variation is easily accomplished merely by loosening the attachment means 22, comprised in clamps 21, whereupon the separate assemblies comprising clamps 21, springs 23, brackets 26 and feet 28 may be slid along the tube 16 to a new position of adjustment. When so positioned, the nut assemblies 22 are again tightened and the beam 13 is supported as before.

To facilitate the work of guiding the beam across the work surface, there is mounted on each end thereof an upstanding loop member 31. These may be engaged by a rope, cable or rigid rod to be grasped by the operators, as indicated in Fig. 1.

In trussing the beam 13, in accordance with the instant invention, there are mounted upon the opposite

ends thereof a pair of upstanding elements 32, one element of each pair being secured on opposite sides of the web portion 15 at each end of the beam. The upstanding arms of each pair of elements 32 project above the associated spring mounting means and may be formed with registering openings 33 to receive a lifting bar or handle 34 (see Fig. 1). Supported between such arms, beneath the openings 33, is a pivot pin 35, the pins defining anchors for the opposite ends of the truss.

The truss itself is indicated generally at 36 and is made up of a pair of rigid tubular members 37 and 38, each having a yoke 39 at its outer end pivotally mounted upon a respective pin 35. The members 37 and 38 extend toward one another from their anchor points in overlying spaced relation to the beam 13 and engage one another in telescoping connection. As shown in Fig. 6, the left hand truss member 37 has a screw threaded stud 41 projecting therefrom upon which is mounted a shouleder stop nut 42 and a lock nut 43. The outer end of the stud 41 is received in the inner end of truss member 38 which limits against the nut 42, a predetermined fixed relationship of the parts being maintained against the effects of vibration by turning the lock nut 43 up into frictional engagement with the nut 42.

Centrally of the beam 13, suspension means are provided interconnecting the beam and the truss 36. These means comprise two pairs of posts 44 fixed to the beam 13 on opposite sides of the engine 19. In overlying relation to each pair of posts 44 is a saddle 45 secured to the truss 36. The opposite ends of each saddle 45 are connected to its associated posts 44 by links made up of a chain 46 and a coil spring 47, the links being crossed diagonally relatively to each other.

The suspension devices and the truss 36 jointly cooperate in inhibiting undesired sagging or bowing of the beam 13 and in obtaining a predetermined flexure of the beam between arched and bowed extremes. In this connection, when an elongated beam such as the beam 13 is supported at or adjacent to its ends it tends to flex downward or to assume a bowed shape. Such tendency may be resisted or controlled by an initial adjustment of the stop nut 42 in the truss which will limit the inward telescoping motion of the truss members 37 and 38 to a predetermined extent. Further, by adjustment of the nut 42 outwardly along the stud 41 the effective length of the truss 36 may be extended to enforce an arching of the beam 13. Such an adjustment is illustrated in Fig. 2 wherein the beam is shown in full lines in a normal flat horizontal plane and is shown in dotted lines as set to an arched form by adjustment of the truss.

Thus, by expansion or contraction of the truss member 36 the flexure of the beam 13 is readily controlled and regulated although the beam is of extraordinary length and only supported adjacent its extremities. Of particular importance is the fact that the present means of strengthening the elongated beam in no way affects its vibratory motion or decreases its efficiency. Although the truss member is restrained by its connection to the central portion of the beam, which is necessary in order to increase the stability of the assembly and prevent tipping or side-sway of the truss member, such tie or connection is of a resilient character so as not to interfere with or decrease the desired vibratory motion of the screed.

From the above description it will be apparent that there is thus provided a device of the character described possessing the particular feature of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features, it is to be understood that the invention is not limited to the specific features shown, but that the means and construction herein disclosed comprise but one of several modes of putting the invention into effect.

Having thus described my invention, I claim:

1. A concrete vibrator, including an elongated beam, vibratory means on said beam, means supporting said beam at its ends for motion over a concrete surface, said beam tending by reason of such support to flex downward, a truss interconnecting the ends of said beam and

extending in overlying spaced relation thereto, and resilient yielding means interconnecting said truss and said beam centrally thereof.

2. A concrete vibrator according to claim 1, characterized by means shortening and extending the length of said truss to effect a corresponding change in the flexure of said beam.

3. A concrete vibrator including an elongated beam, vibratory means on said beam, means supporting said beam at its ends for motion over a concrete surface, said beam tending by reason of such support to flex downward, a truss for said beam comprising rigid truss members anchored at their one ends to respective ends of said beam and extending toward one another in overlying spaced relation to the beam and joined in an adjustable connection at their opposite or adjacent ends, said connection including means to vary the effective length of said truss, and resilient suspension means interconnecting said truss and said beam centrally of the beam.

4. A concrete vibrator including an elongated beam, vibratory means on said beam, means supporting said beam adjacent its ends for motion over a concrete surface, said beam tending by reason of such support to flex downward, a truss rigidly interconnecting the ends of said beam and lying in spaced overlying relation to the length thereof, and resilient suspension means interconnecting said truss and said beam centrally of the beam.

5. A concrete vibrator including an elongated beam, vibratory means on said beam, means supporting said beam adjacent its ends for motion over a concrete surface, said beam tending to flex downward between said supports, a truss for said beam comprising rigid arcuate truss members anchored at their one ends to respective ends of said beam and extending toward one another in overlying spaced relation to the beam into a telescoping connection at their opposite or adjacent ends, a nut on one of said truss members engageable by the other of said members to limit inward telescoping motion of said members and thereby limit the downward flexure of said beam, and a screw threaded mounting for said nut permitting adjustment thereof to vary the effective length of said truss and thereby to vary the flexure of said beam between bowed and arched extremes.

6. A concrete vibrator according to claim 5, characterized by resilient suspension means interconnecting said truss and said beam centrally of the beam.

7. An elongated screed beam for finishing cementitious surfaces resiliently suspended upon a pair of adjustably spaced feet characterized by a truss member interconnected with the opposite ends of the beam and extending in overlying parallel spaced relation with said beam, means for varying the length of said truss to control the flexure of said underlying beam, resilient links interposed between the beam and overlying truss centrally thereof and means for adjustably securing the spaced feet to the beam independently of the connection of the truss thereto comprising an expandable and contractible clamp carried by each of said feet and means for contracting said clamp upon the beam in any desired position of adjustment relative thereto, the construction and arrangement being such that the feet may be adjusted relative to the beam irrespective of the interconnection of the truss member with the ends of the said beam.

8. In a semi-flexible elongated vibratory screed beam, rigid tie means interconnected with opposite ends of the beam and extending into overlying parallel spaced relation with said beam, means for varying the effective length of said rigid tie means to thereby control the degree and direction of flexure of said beam, and resilient stabilizing links interposed between said beam and overlying tie member and connected thereto, the links extending in upward diagonal intersecting planes to thereby increase the stability of said vibratory screed beam.
